The ornamental design for an electric grinder for sharpening knives, as shown and described.

Feb. 1, 2011 (JP) 2011-002126

DESCRIPTION

(51) **LOC (10) Cl.** **08-05**

FIG. 1 is a perspective view of an electric grinder for sharpening knives showing one embodiment of my new design;

(52) **U.S. Cl.**

FIG. 2 is a front elevational view thereof;

USPC **D8/63**

FIG. 3 is a rear elevational view thereof;

(58) **Field of Classification Search**

FIG. 4 is a top plan view thereof;

USPC D8/63, 93, 34, 91, 35; D7/698; 451/45,
451/267, 259, 198, 193, 177, 555, 132, 194,
451/241; 36/31; 76/86-89; 30/138

FIG. 5 is a bottom plan view thereof;

See application file for complete search history.

FIG. 6 is a left side elevational view thereof; and,

(56) **References Cited**

FIG. 7 is a right side elevational view thereof.

U.S. PATENT DOCUMENTS

The article is an electric knife sharpener for sharpening a knife by inserting the edge of a cutting tool, such as a kitchen knife, into a groove provided in a lid attached to the top. The knife is sharpened at the peripheral surface of a truncated cone-shaped grind stone. Provided at the center of the lid is a hole formed into a wheel shape, and water is poured therethrough. Unused water and water used for sharpening are accumulated in a discharge cup attached to the lateral side. The discharge cup is detachable and can be detached to allow the discharge water accumulated in the discharge cup to be discarded.
